Attorneys

UNITED STATES PATENT OFFICE.

ETHAN I. DODDS, OF PITTSBURGH, PENNSYLVANIA, ASSIGNOR, BY MESNE ASSIGNMENTS, TO FLANNERY BOLT COMPANY, OF PITTSBURGH, PENNSYLVANIA, A CORPORATION OF DELAWARE.

STAY-BOLT STRUCTURE.

Application filed August 29, 1919. Serial No. 320,730.

To all whom it may concern:

Be it known that I, ETHAN I. Dodds, a citizen of the United States, and a resident of Pittsburgh, in the county of Allegheny and State of Pennsylvania, have invented certain new and useful Improvements in Stay-Bolt Structures; and I do hereby declare the following to be a full, clear, and exact description of the invention, such as will enable others skilled in the art to which it appertains to make and use the same.

This invention relates to improvements in staybolt structures for boilers,—the object of the invention being to provide a simple mounting for the headed end of a staybolt at the outer boiler sheet, with the use of a bearing member resting against the outer face of the sheet, thus obviating the necessity of inserting any part of the bearing member into or through the boiler sheet, and to enclose said bearing member in such manner as to prevent leakage and so that necessity for securing the said bearing member to the boiler sheet shall be rendered unnecessary.

With this and other objects in view, the invention consists in certain novel features of construction and combinations of parts as hereinafter set forth and pointed out in the claims.

In the accompanying drawings; Figure 1 is a sectional view illustrating a staybolt structure embodying my invention, and Figure 2 is a view showing the application of my improvements to a boiler sheet from which a threaded sleeve or bushing has been removed.

1 represents the outer sheet of a boiler and 2 the inner sheet. The outer sheet is provided with openings such as indicated at 3 for the accommodation of staybolts, such as shown at 4, and the inner ends of said staybolts are secured to the inner boiler sheet in any suitable manner.

The opening 3 in the outer boiler sheet may be drilled through the sheet, or it may be the threaded opening 3^a from which a threaded bearing sleeve has been removed as shown in Figure 2, but in either case the opening will have such form and dimensions as to permit the lateral swing or play of the

staybolt customary with staybolt structures of the "flexible" type.

A bearing member in the form of a ring 5 is provided with a curved seat 6 for the rounded head 4^a of the staybolt 4 and the inner portion of the inner wall of the ring or bearing member is beveled as at 6^a. The ring or bearing member 5 rests freely against the outer face of the outer sheet 1 with its inner edge portion overlying a portion of the bolt opening 3 or 3^a. The bearing member thus forms a ring seat for the bolt head disposed against the boiler sheet.

A cap or closure 7 encloses the annular bearing member or ring 5 and also the head of the staybolt. The edge or end of the cap 7 engages the outer face of the boiler sheet 1 and said cap is integrally united to the sheet 1 by a weld 8. This weld is composed of a suitable alloy and is applied around the cap so that it becomes an integral part of both the cap and the boiler sheet,—the integral union of the cap and boiler sheet being thus so intimate that the effect of leakage of steam past the bearing member or the seat of the bolt head thereon will be effectually prevented.

It will be observed that with my improvements, no special formation of the wall of the bolt opening is necessary and that the opening which may previously have been occupied by a threaded bearing sleeve may be utilized.

My improvements permit a bolt with a small head to be connected with a boiler sheet when the opening in the latter is large as compared to the size of the bolt head and facilitates the installation of staybolts where the outer boiler sheet is at an angle to the inner boiler sheet.

Having fully described my invention what I claim as new and desire to secure by Letters Patent, is:—

1. In a staybolt structure, the combination with a boiler sheet having an opening, and a staybolt having a head smaller than said opening, of a bearing member for the head having an opening therein, disposed freely against the outer face of the boiler sheet and overlying a portion of the opening in the latter, and a cap enclosing said

bearing member and the head of the bolt and fixed to the boiler sheet.

2. In a staybolt structure, the combination with a boiler sheet having an opening, and a staybolt having a head, of a bearing ring resting against the outer face of the boiler sheet and having its opening appreciably less in diameter than the opening in

the boiler sheet, and a cap fixed to the boiler sheet around said bearing ring and engaging therewith to prevent lateral displacement of the latter. ¹⁰

In testimony whereof, I have signed this specification.

ETHAN I. DODDS.
